Primary Examiner — Sandra Snapp(57) **CLAIM**

The ornamental design for a dispensing cap, as shown and described.

DESCRIPTION

FIG. 1 is an isometric view of a top, front, and left side of an ornamental design for a dispensing cap;

FIG. 2 is a front elevational view of the dispensing cap of FIG. 1;

FIG. 3 is a rear elevational view of the dispensing cap of FIG. 1;

FIG. 4 is a left side elevational view of the dispensing cap of FIG. 1, the right side elevational view being a mirror image thereof;

FIG. 5 is a top plan view of the dispensing cap of FIG. 1; and, FIG. 6 is an isometric view of a top, front, and left side of the dispensing cap of FIG. 1, wherein a lid is shown in a closed position.

It is understood that the boundary of the claimed design is represented by the shade and solid lines defining the apertures. The surface shown with broken shade lines in FIGS. 1 and 5 forms no part of the claimed design. The broken lines are for the purpose of illustrating environmental structure and form no part of the claimed design.
